UNITED STATES PATENT OFFICE.

HENRY KLECKLER, OF BUFFALO, NEW YORK, ASSIGNOR TO CURTISS AEROPLANE AND MOTOR CORPORATION, A CORPORATION OF NEW YORK.

AEROPLANE-CONTROL MECHANISM.

1,336,632.

Specification of Letters Patent. Patented Apr. 13, 1920.

Application filed August 10, 1917. Serial No. 185,520.

To all whom it may concern:

Be it known that I, HENRY KLECKLER, a citizen of the United States, residing at Buffalo, in the county of Erie and State of New York, have invented certain new and useful Improvements in Aeroplane-Control Mechanism, of which the following is a specification.

My invention relates to aeroplane control mechanism and embodies a structure in which the control leads approximately parallel the mechanism itself. The invention is further characterized by the mounting of one or more of the guides upon the movable control-wheel supports in a manner permitting of such movement without correspondingly moving the guide. This latter construction is advantageous in that the control lead is held taut and positively in sliding engagement with the guide irrespective of the position of the support. The former construction is desirable in that maximum operating space is accorded the pilot in close proximity to the control. Still another characteristic of the invention is the interconnection of dual control wheels or devices without extending the interconnection directly between the devices. Moreover, the arrangement of the guides or pulleys is such that the control leads of the dual control (by removing the interconnection) may be conveniently used in a single acting capacity.

Of the drawings:

Figure 1 is a front elevation of the improved dual control mechanism constituting the invention hereinafter claimed;

Fig. 2 is a top plan view of the mechanism illustrated in Fig. 1, and

Fig. 3 is an end elevation with a portion of one of the walking beams broken away.

In its broad aspect it is apparent that the mounting of the guides and pulleys and the ensuing arrangement of the control leads is such that a dual control mechanism is non-essential, although admittedly preferred. By removing either one or the other of the control devices constituting a part of the dual mechanism and re-arranging the control leads, the use of the control in a single acting capacity is obviously practical. In each instance, whether dual or single, the control lead or leads should follow the lines of the mechanism rather than extend out

right and left from the control wheel or drum as heretofore. Furthermore, in either instance, the mounting of the terminal pulleys should be carried out in the manner herein set forth so that the cable leads may be retained taut regardless of the degree of oscillation accorded the control wheel support.

The control mechanism is designated in its entirety by the numeral 10. It comprises a shaft 11 terminally equipped with walking beams 12 of a peculiar construction conducive to lightness and increased strength. These beams 12 are mounted for oscillation with the shaft 11 and are connected by appropriate connections 13 with the elevator flaps (not shown). Intermediately the shaft 11 is equipped with suitably spaced columns 14 arranged preferably at points equidistantly removed from the immediate point of the shaft. Said columns are braced as at 15 to the shaft 11 and terminally equipped, each with a control wheel 16. As intimated, the control wheels 16 may be separately or simultaneously operated to effect control.

The outer end of each column 14 is elbowed as at 17 for the appropriate mounting of the control wheel shaft. Each shaft, designated 18, (in each instance) carries a pair of guides or drums. These drums, 18 and 19 lie respectively in advance of and to the rear of the elbow 17 and may be described as mounted upon the extended axis of the wheel.

At the foot of each column 14 a pair of guides or pulleys 20 and 21 are disposed. These pulleys, like the pulleys 18 and 19 are commonly supported one about the extended axis of the other, one in advance of and one to the rear of said column. The pulley 20 will be hereinafter referred to as the pulley corresponding to the guide 18 and the pulley 21 to the guide 19. This description is believed to be appropriate in that the axes of the several guides and pulleys lie parallel although in different planes. The mounting for each pair of foot pulleys is of the bracket type and designated 22. Moreover, the axis of the shaft 11 is substantially tangent to the grooved peripheries of the several pulleys 20 and 21. Laterally out from the pulleys 20 and 21, and in close proximity to each walking beam 12,

guides 23 are disposed. These guides can be described as floating in that they are mounted loose upon the shaft 11 and in such manner that movement of the shaft is effected without correspondingly moving said guides. In other words, the guides are fixed with respect to the axis of their supporting shaft. The particular mounting for these guides 23 is best illustrated in Fig. 2. Each 5 guide or pulley is equipped with the conventional pulley housing 24 and with legs 25 which extend out from the housing 24 to straddle the shaft 11. A collar 26, loosely mounted upon the shaft 11, fits between the 10 legs 25 of the pulley housing to serve as the pulley support. The connection between the leg 25, and the collar 26 for each pulley is preferably a pivot connection and is designated 27. This arrangement of the guides 15 or pulleys 23 at the extremities of the shaft 11 is such that the control leads 28 which interconnect respectively the wheels 16 and the control surfaces (not shown) may follow approximately the lines of the control 20 mechanism to a convenient point of departure remote from the position occupied by the pilot or pilots in directing flight. In tracing the path of the leads 28 it will be noted that they extend forwardly to the pulleys 23 thence inwardly approximately parallel with the axis of the shaft 11 to the pulleys 20 and thence upwardly approximately parallel with the columns 14 to the drums or guides 18 mounted at the column 25 ends. Wheel manipulation is thus effective in directing control.

For a dual control it is essential that the control devices be interconnected when the control surfaces are double acting. Obviously a direct connection between the control wheels is objectionable. To so connect them would hamper the pilot or pilots in directing control and prevent access to the pilot seats between the control devices. The 30 interconnection between said devices is designated 29. It comprises an endless cable or lead arranged to approximately parallel the axis of the shaft 11 and the columns 14 throughout its length. The guides 19 and 35 the pulleys 21 serve as the cable guides.

Through rotation of the wheels to either the right or left the balancing surfaces, if double acting, are moved simultaneously, one up and one down, *i. e.*, to assume respectively a positive and a negative angle of incidence. The control leads, under all circumstances, follow the control mechanism to a convenient point of departure that the useful space in the vicinity of the control 40 mechanism may be increased and control enhanced. The mounting of the terminal pulleys 23 avoids slack in the control leads as does also the mounting of the pulleys 20 in such manner that the axis of the shaft 11 45 lies tangent thereto. Appropriate interme-

diate and terminal bearings effectually support the shaft.

While in the foregoing there has been illustrated in the drawings and described in the specification such combination and arrangement of elements as constitute the preferred construction or embodiment of this invention, it is nevertheless desired to emphasize the fact that interpretation of the invention should only be conclusive when 75 made in the light of the subjoined claims.

What is claimed is:

1. In aeroplane control mechanism, a control device, a movable support, a guide loosely mounted upon said support in such 80 manner that the support may be moved without correspondingly moving said guide, the axis of the guide and the axis of the support being unaligned and removed one from the other, and a control lead trained 85 over said guide for manipulation by movement of said device.

2. In aeroplane control mechanism, a control wheel, an oscillatable support, a guide loosely mounted upon said support with its 90 axis substantially at right angles to and fixed with respect to the axis of oscillation of said support, and a control lead trained over said guide for manipulation by movement of said wheel.

3. In airplane control mechanism, a support, separate columns carried by the support, separate control devices mounted upon the ends of the columns, separate control leads for the different control devices, the 100 control leads in each instance being extended off from the control devices in the direction of the length of the columns, and a connection between the separate control devices likewise extended off therefrom in the direction of the length of the columns, the connection for a portion of its length lying closely adjacent and in parallelism with the support.

4. In aeroplane control mechanism, a shaft, 110 separate columns erected upon said shaft, a control wheel carried by each column, a control lead for each wheel, guides for the control leads arranged to approximately parallel the paths of the control leads with 115 the columns and shaft axis respectively, and an interconnection between said wheels correspondingly arranged in approximate parallelism with the columns and shaft axis respectively.

5. In aeroplane control mechanism, a support, separate control devices mounted upon said support, either of which may be manipulated for effecting control, separate control leads, one for each device, guides for the 125 control leads arranged to approximately follow the lines of said support, and an interconnection between the control devices correspondingly arranged.

6. In aeroplane control mechanism, a 130

shaft, columns erected upon said shaft, a control device mounted at the outer end of each column, pairs of guides mounted respectively at the foot of and at the outer 5 end of each column, separate control leads arranged to contact the corresponding guides of each pair, and an interconnection

between the control devices similarly arranged, said interconnection engaging the remaining guide of each pair. 10

In testimony whereof I hereunto affix my signature.

HENRY KLECKLER
